UNITED STATES PATENT OFFICE.

THOMAS LYDWELL ECKERSLEY, OF DANBURY, ENGLAND, ASSIGNOR TO RADIO CORPORATION OF AMERICA, A CORPORATION OF DELAWARE.

RADIO TRANSMITTING SYSTEM.

Application filed June 11, 1924, Serial No. 719,246, and in Great Britain June 27, 1923.

Filter circuits, chains of inductances and capacities have been extensively used in receiving and telephone circuits for the purpose of eliminating undesired frequencies, but have not yet been successfully applied in transmitting valve circuits to cut out the undesirable harmonics which are radiated when the set is working efficiently.

This failure is due to the fact that when 10 the filter is placed between the valve set and the aerial in the feed circuit of the former, oscillations of the natural period of the filter circuit are set up, owing to the presence of capacity reaction in the valves 15 and other spurious reaction which cannot be eliminated.

Even when it is possible, by careful balancing to eliminate these spurious oscillations, the arrangement is inefficient, on 20 account of the high impedance of the feed circuit to the high frequency harmonics.

According to this invention, these difficulties are obviated by the use between the anode feed circuit and the filter circuit of 25 a closed oscillatory circuit tuned to the fundamental frequency. The filter circuit is shunted across a suitable fraction of the inductance of the closed circuit, or is coupled thereto.

30 The tuned circuit acts as a filter for any oscillations in the filter circuit, the frequency of which differs from that of the tuned circuit and therefore the potentials applied by these oscillations to the plate of the valve, and 35 by capacity reaction to the grid are relatively small and the tendency to self oscillation is reduced to a minimum.

Keying with such an arrangement is preferably effected by arranging a resistance in 40 parallel with the aerial tuning inductance and alternately connecting one of the end terminals of the filter circuit to the resistance and to the inductance. By suitably adjusting the value of the resistance, the load on 45 the valve may thus be kept constant.

My invention is illustrated by the accompanying drawing, in which

Figs. 1 and 2 are diagrammatic representations of circuits embodying the invention. 50 In each of the figures corresponding parts are indicated by the same reference characters.

In the drawings 1 is the main oscillating valve and 2 is the inductance in the anode 55 circuit thereof.

In Fig. 1 L_1 , C_1 is the closed circuit tuned to the transmitting wave length. This circuit is closely coupled to the inductance 2, and also to an inductance 3 across one end of a filter circuit, the other end of which is 60 formed of an inductance 4 coupled to the aerial 5.

A similar arrangement is shown in Fig. 2 but in this modification the input and output of the filter are direct coupled to inductances L_1 and 5 respectively.

The filter circuit illustrated, consists of a series of inductances 6 and shunt condensers 7. The first and last of the inductances 6 are of a value half that of the intermediate 70 inductances.

The conditions which determine the value of each of the intermediate inductances and of the condensers, are that $p^2 LC=2$ where $p=2\pi \times$ frequency, and that the ratio of the 75 voltage across the filter to current through the filter should be equal to $\frac{pL}{2}$. This choice

of constants ensures that (1) the amplitude of the fundamental frequency n is unchanged in transmission along the filter, and (2) all harmonics are reduced to a small amplitude which depends on the number of stages of the filter.

The coils 3 and 4 should be provided with 80 a large number of adjustable tappings. The tapping on the coil 4 should be such that the impedance of the filter should be as above stated. The tapping on the coil 3 determines the ratio of the current in the circuit L_1 , C_1 85 to that in the aerial. This ratio should not be made too small, otherwise the difficulty of avoiding the natural oscillations of the filter circuit will reappear.

Other forms of filter circuit may 90 obviously be employed. Thus, the end inductance 6 may be omitted and each of the end condensers may have a capacity twice that of each of the intermediate condensers. Or, the intermediate inductances may be 95 arranged in the two sides of the filter circuit alternately, instead of being all on the one side, as shown in the figure.

Having described my invention what I claim is:—

1. In a transmitting system, the combination with a valve generator and a filter circuit consisting of a plurality of series inductances with parallel capacities therebetween whereby the fundamental frequency 110

generated is passed and the harmonics suppressed by said filter circuit, of a closed oscillatory circuit tuned to the fundamental frequency and interposed between the valve generator and the filter circuit.

2. In a transmitting system the combination with a valve generator, an anode circuit therefor, a filter circuit consisting of a plurality of series inductances with parallel capacities therebetween whereby the fundamental frequency generated is passed and the harmonics suppressed by said filter circuit, an oscillatory link circuit external to the generator tuned to the fundamental frequency coupled to the anode circuit of said generator and the filter circuit.

3. In a transmitting system, the combination with an aerial circuit a valve generator, an output circuit therefor, a filter circuit consisting of a plurality of series inductances with parallel capacities therebetween whereby the fundamental frequency generated is passed and the harmonics suppressed by said filter circuit between the valve output and the aerial circuit, and a circuit tuned to the fundamental frequency generated, and external to the generator interposed between the output of the valve and the filter.

4. In a transmitting system, the combination with a valve generator and a filter circuit consisting of a plurality of series inductances with parallel capacities therebetween whereby the fundamental frequency generated is passed and the harmonics suppressed by said filter circuit, an oscillatory circuit external to the generator tuned to the fundamental frequency generated and inductively coupled to the filter and the output of the valve.

49 5. In a transmitting system, the combination with a valve generator and a filter circuit consisting of a plurality of series in-

ductances with parallel capacities therebetween whereby the fundamental frequency generated is passed and the harmonics suppressed by said filter circuit, of an oscillatory circuit tuned to the fundamental frequency conductively coupled to the inductance of the filter and inductively coupled to the output of the valve.

50 6. In a transmitting system a valve generator, an output circuit therefore, a variable inductance for said output circuit, a filter circuit associated with said output circuit and an oscillatory link circuit external to said generator coupled to said output circuit and to said filter circuit and tuned to the frequency to be transmitted whereby all oscillations set up in the filter circuit except those at the fundamental frequency are prevented from reacting on said generator.

55 7. In a transmitting system a valve generator, a filter circuit consisting of a series of inductances and parallel capacities therebetween, the end inductances of said series being of a value half that of the intermediate inductances, said intermediate inductances and condensers being so chosen that $LC = (1 - 2\pi^2 f^2)$, coupled to said generator, and an oscillatory circuit tuned to the fundamental frequency and coupled to said generator and said filter circuit.

70 8. In a transmitting system a valve generator a filter circuit consisting of a series of inductances and parallel capacities therebetween, the inductances and capacities of said filter being so chosen that the ratio of the voltage across the filter to the current through the filter is equal to $\pi f L$ coupled to said generator, and an oscillating circuit tuned to the fundamental frequency and coupled to said generator and said filter.

75 THOMAS LYDWELL ECKERSLEY.
